(57) **CLAIM**

The ornamental design for a side mirror for a vehicle, as shown and described.

DESCRIPTION

FIG. 1 is a rear perspective view of a first embodiment of a side mirror for a vehicle according to our novel design;

FIG. 2 is a front view thereof;

FIG. 3 is a side view thereof; and

FIG. 4 is a rear view thereof;

FIG. 5 is a top view thereof; and

FIG. 6 is a bottom view thereof.

FIG. 7 is a rear perspective view of a second embodiment of the side mirror for a vehicle according to our novel design;

FIG. 8 is a front view thereof;

FIG. 9 is a side view thereof; and

FIG. 10 is a rear view thereof;

FIG. 11 is a top view thereof; and,

FIG. 12 is a bottom view thereof.

In the drawings, the broken lines show the inner base of the side mirror for a vehicle and form no part of the claimed design.
